GRINDING METHOD

Clifford L. Garrison, Adrian, Mich., assignor to
 Oliver Instrument Company, Adrian, Mich., a
 corporation of Michigan

Application July 26, 1947, Serial No. 763,781

1 Claim. (Cl. 51—281)

1
 This invention relates to a method of forming, grinding or sharpening tools and more especially to a method of configurating or sharpening form tool bits manufactured of relatively hard materials.

In the manufacture of form tool bits of the character used in machine work for cutting metals and alloys, it has been a recent practice and development to form such tool bits from metal alloys which are extremely hard. By way of example, cutting tools and form tool bits are being fashioned from an alloy known as tungsten carbide. At the present time this alloy is one of the hardest known materials. The production of the form tools or cutting tools from this material presents a problem of configurating the tool form by grinding and of resharpening by reason of the fact that the conventional type of abrasive or grinding wheel does not satisfactorily grind or sharpen tools fabricated of this material. When a tool bit formed of comparatively hard metal alloy is brought into contact with the conventional grinding wheel, the tendency is to result in a "burning of the tool" in which the cutting edge does not become sharp but becomes chipped or broken presenting an uneven cutting edge, and the grinding wheel surface becomes "glazed" by reason of its contact with the hard material.

An object of the present invention is the provision of a method of grinding or sharpening a cutting tool of relatively hard material whereby the grinding operation may be performed in a short space of time and a smooth cutting edge formed upon the tool or cutting instrumentality.

Another object of the invention is the provision of a method of grinding or sharpening a cutting or form tool by impact of a grinding or abrasive medium with the tool.

Another object of the invention resides in a method of grinding utilizing a grinding wheel especially configurated in a manner providing zones adapted for intermittent engagement with the tool by impact in a manner which substantially eliminates glazing of the wheel and whereby the life of the grinding wheel is greatly prolonged.

Still another object of the invention resides in a method of grinding utilizing a grinding apparatus in which a grinding medium having a mutilated grinding area is arranged for cooperation with a tool supporting means whereby the extent of movement of a tool carried by the tool supporting means into engagement with the grinding wheel is predetermined or restricted whereby a grinding or sharpening operation upon a tool may be quickly and efficiently completed.

A further object of the invention resides in a

2
 method of grinding utilizing an apparatus for sharpening or grinding tools of comparatively hard material wherein a complete tool grinding or forming operation may embrace a series of consecutive grinding or tool forming cycles, each of the cycles being limited to removing a comparatively small amount of metal from the tool to be formed or sharpened, each metal removing operation being carried out by impact of spaced grinding areas or zones provided upon the wheel or grinding medium.

Further objects and advantages are within the scope of this invention such as relate to the arrangement, operation and function of the related elements of the structure, and to economies of manufacture and numerous other features as will be apparent from a consideration of the specification and drawing of a form of the invention, which may be preferred, in which:

20 Figure 1 is a side elevational view showing a portion of a grinding apparatus utilized in the grinding method of my invention, certain parts being shown in section for purposes of illustration;

25 Figure 2 is a front elevational view of the portion of the grinding apparatus illustrated in Figure 1;

Figure 3 is a fragmentary sectional view taken substantially on the line 3—3 of Figure 2;

30 Figure 4 is an elevational view of a grinding or abrasive element utilized in my invention;

Figure 5 is a sectional view through the grinding element taken substantially on the line 5—5 of Figure 4;

35 Figure 6 is an elevational view of a modified form of grinding apparatus utilized in my invention;

Figure 7 is a front elevational view of a form of an abrasive means or unit utilized in my invention;

40 Figure 8 is a side view of the abrasive unit illustrated in Figure 6, certain parts of the construction being shown in section, and

Figure 9 is an isometric view illustrating one of the segments of abrasive material forming an element of the abrasive unit.

While I have illustrated forms of my invention involving the use of a rotary abrasive unit or means for forming, grinding or sharpening form tools or cutting instrumentalities, it is to be understood that I contemplate the utilization of the method of forming, grinding or abrading wherever the same may be found to be useful and to employ the apparatus for removing material by impact of an abrading medium with various forms of objects fabricated of hardened material.

Referring to the drawings in detail, the grind-

ing apparatus illustrated in Figures 1, 2 and 3 is inclusive of a base 10 upon which is supported an upwardly projecting frame 11. Surrounding the lower portion of frame 11 is an outwardly extending uniplanar portion 12 bounded by an upwardly extending flange 14, the construction providing a receptacle or basin arranged to receive fluid that may be directed against the grinding or abrasive wheel surface for cooling the grinding wheel and object being ground. The base 10 incloses a suitable fluid pump (not shown) through which fluid in a reservoir contained in the base 10 is directed under pressure through a pipe 15 and a flexible conduit 16 to a manifold 17 from which fluid, guided by a channel-shaped portion 24, is ejected upon the surface of the abrasive wheel 18.

The grinding or abrasive medium in the form of a wheel 18 is mounted upon a shaft 19 which is journaled in suitable bearings (not shown) carried in the frame member. The shaft 19 is provided with a pulley 20 driven by a belt 21 connected to a suitable motor (not shown), the pulley 20 and belt 21 being enclosed in a suitable guard 24. The grinding wheel 18 is substantially enclosed within a housing 22 which is supported upon the frame 11 by means of a shaft 23 supported in bearings carried by the frame. The housing is arranged for adjustment about the axis of shaft 23. To accomplish this adjustment, the frame of the machine is provided with a boss 25 which is bored to accommodate a shaft 26, the latter being provided with an operating or hand wheel 27 at one end, the other end portion being threaded into a nut or bushing 29. The bushing 29 is pivotally supported upon a projection 31 formed integrally with the frame 11. Thus by rotating the hand wheel 27, the shaft 26 being threaded into bushing 29, the grinding wheel housing 22 may be moved about the axis of shaft 23. The purposes of this adjustment will be hereinafter explained.

The forward portion of the grinding wheel housing 22 is formed with vertically extending ways or tracks 32 of dove-tailed cross section upon which is slidably supported a member 34. The housing 22 is formed with a boss portion 36 which is bored to accommodate a bushing 37. The bushing 37 is fixed in the boss 36 and is inferiorly threaded to receive the threaded portion 38 of a shaft 41. Secured to the upper extremity of member 34 is a bracket 39 having a boss portion 40 bored to receive the unthreaded portion of shaft 41 as shown in Figure 1. Mounted upon the upper end of the shaft 41 is a hand wheel 43 for rotating the shaft. Rotation of shaft 41 by means of hand wheel 43 provides a means for raising or lowering the member 34 for a purpose to be hereinafter explained.

In configurating form tools, a template is utilized with a suitable tool holder for reproducing the tool form on the tool bit. The apparatus illustrated is inclusive of a template forming or grinding wheel 48 mounted upon a shaft 49 actuated by an electrically-operated motor 50. The motor 50 is mounted upon a platen 51 which is longitudinally adjustable through the medium of a threaded shaft 52, the latter provided with a hand wheel 53 for rotating the shaft. The shaft 52 extends through a threaded bushing 54 carried by the frame of the machine so that rotation of the hand wheel 53 moves the platen 51, motor 50 and template forming wheel 48. A tool holder supporting means in the form of a semi-spherically shaped member 57 is mounted upon

a ledge 58 formed on the frame of a machine and is adapted to accommodate a combined tool holder and template carrying means 60. Also mounted upon the machine frame 11 is a gage or abutment block 61 carried in a mounting bracket 62, the latter being secured to the machine frame by suitable screws.

The holder 60 may be utilized to configurate or profile a template 63 to the shape of a master form tool by utilizing the template grinding wheel 48 in the following manner: The tool holder 60 is provided with means in the form of a block 64 provided with a suitable groove or recess to receive a form tool bit. A pivotally supported cam 65 is arranged for engagement with the lower surface of the form tool carrying block 64 for wedgedly locking the form tool in the block 64, the cam 65 being moved to locking position under the influence of a threaded member 66. With the form tool so mounted in the tool holder 60, the latter is disposed with a semi-spherical recess 67 formed in the lower extremity thereof fitted over the ball-shaped support 57, the template 63 being in a position to engage the template grinding wheel 48. The operator moves the tool and template holder 60 in a direction to bring the template blank 63 into engagement with the grinding wheel 48 until all portions of the master tool bit are brought into engagement with the abutment 61. When this occurs, the grinding or profiling of the template 63 ceases because the abutment 61 cooperates with the form tool bit as a limiting means for determining the extent of grinding or abrasion of the template blank 63.

The machine is also provided with a gaging means for coordinating a form tool blank or bit to be ground or resharpened to the configuration of the finished template. In this connection the machine frame 11 is provided with a second spherically-shaped support 70 adapted to accommodate the template and tool holder 60. Disposed above the support 70 is a gage plate or block 71 arranged so as to be engaged by form tool blank carried by the holder 60 when the latter is in engagement with the support 70. Mounted upon the machine frame is a bracket 73 provided with a gage block 74 which has a threaded tenon (Figure 3) extending through a bushing carried by the bracket 73, this arrangement forming a micrometer adjustment for the gage block 74 whereby the latter may be adjusted to a particular position for determining the amount of metal to be removed from the form tool bit or blank during a grinding operation. Thus by proper setting of the gage block 74, in contact with a template form 63 carried by the tool holder 60, the form tool blank may be brought into engagement with the gage plate 71 and locked in position so that when the form tool is subsequently brought into engagement with the grinding wheel 18, only the desired amount of metal will be removed from the form tool.

In forming, grinding or resharpening form tools of the character shown at 71 in Figure 1, the relatively slidably member 34 is provided with a semi-spherically shaped tool holder support 78 which is also adapted to fit the recess 67 formed in the tool holder 60. The upper portion of member 34 is provided with a straight edge 80 which is arranged to operate as a gaging means or movement-limiting means for the tool holder 60 and tool bit 71 by reason of engagement of the template 63 therewith. The template 63 is removably secured to the tool and template holder 60 and is held in position by means of a thumb

screw 81 so that templates of other forms or sizes may be interchanged.

In grinding or sharpening form tools of the character shown at 71, it is usual to provide a relief angle 79 adjacent the cutting edge of the tool. In the apparatus illustrated, the member 34, adapted to carry the tool holder and template support 60, is vertically slideable through rotary movement of the hand wheel 43 so that the form tool 71 may be caused to engage the wheel 18 in different relative positions for varying the relief angle formed on the tool bit.

Heretofore in grinding or sharpening form tools of very hard materials, as for example, tools formed from tungsten carbide alloys or other very hard metal alloys, it has been found that in using a grinding or abrasive wheel presenting a continuous surface, that the form tool of hardened metal tends to become "burned" and is not ground or sharpened so as to present a clean, sharp cutting edge. Moreover the ordinary abrasive or grinding wheel fails to effectively grind or cut such hard tool and the surface of the wheel very soon becomes "glazed" and fails to function satisfactorily. In the present invention I have provided a method of configurating or abrading hard materials by utilizing a grinding or abrasive wheel 18 which is provided with a series of spaced grinding zones or elements for intermittent engagement with the tool to be ground. As particularly shown in Figures 1, 2, 4 and 5, the grinding wheel or unit 18 is formed with a plurality of radial recesses 84, which recesses divide the peripheral portion of the grinding wheel 18 into a plurality of circumferentially spaced segments or zones 85. The recesses 84 are of considerable radial depth so that the segments 85 have a useful life until worn to the depth of the recesses. The unit may be moulded of an agglomerate of abrasive particles held together by a suitable cement or bonding agent. In the use of the grinding unit 18, assuming the latter to be rotating in a clockwise direction as viewed in Figure 1 and counterclockwise as viewed in Figure 4, the edges 86 formed by the juncture of a wall of each of the recesses 84 and the peripheral arcuate surface of each of segments 85 are adapted to successively strike the tool bit 71. The recesses 84 are of a peripheral width greater than the thickness of the tool bit 71 so that during a grinding operation, while the operator is urging the tool holder 60 in a direction to bring the tool bit 71 into contact with the grinding wheel, the tool bit slightly enters each successive recess 84 as the same moves into registration with the tool bit so that the portion of the tool being ground or configurated is struck by each edge 86 of a grinding segment 85 during rotation of the grinding wheel. I have found that the rapid successive impacts of the grinding wheel segments with the portion of the tool bit to be formed or sharpened, very quickly and efficiently abrade or cut away the hard metal of the tool bit, providing a sharp cutting edge upon the form tool and without "glazing" the grinding wheel surface.

In the utilization of the method of my invention of grinding tools, means are provided for limiting the distance that the tool bit may move toward the grinding wheel during each grinding operation. This is an important feature of the invention for the reason that should the form tool bit be permitted substantial movement in a direction toward the grinding wheel, such excessive movement would permit the tool to move too

deeply into one or more of the recesses 84 which would result in damage to the grinding zones or segments and possible damage to the machine. I have found that in employing the method of my invention it is practicable to remove about five thousandths of an inch of metal from the tool bit at each individual grinding cycle or operation. To prevent excessive movement of the tool bit toward the wheel, the tool holder 60, bearing a tool bit 71 to be ground and a template 63 for controlling the form of the tool, is placed in cooperative relation with the support 70 of the gagging means. To adjust the tool bit for the removal of five thousandths of an inch of metal, the micrometer gage block or abutment 74 is rotated until it projects forwardly from normal position a distance of ten thousandths of an inch. The template 63 is then caused to contact the gage abutment 74 and the form tool 71 re-adjusted by manipulation of the cam 65 and retaining screw 66 until the end of the form tool is in contact with the abutment plate 71. As the tool holder support 70 becomes in effect a fulcrum for the tool holder support 60, and as the distance from the center of the support 70 to the template 63 is substantially twice the distance of the center of the support 70 to the upper or cutting edge of the tool bit 71, the tool bit will be in a position relative to the template so that five thousandths of an inch of metal may be removed when the tool bit is brought into engagement with the grinding wheel 18. After the tool bit 71 has been adjusted into contact with the abutment plate 71 and the cam 65 brought into locking engagement with the block 64, the holder 60 is transferred to the support 78 with the template 63 adjacent but out of engagement with the straight edge or template movement-limiting means 80 as shown in Figure 1. With the tool holder in this position the operator exerts a force upon the same in a direction toward the grinding wheel, bringing the tool bit into forcible engagement with the grinding wheel. As the grinding wheel rotates, the recesses 84 are brought into consecutive and rapid registration with the tool bit 71, the latter being projected slightly into each recess. This projection of the tool into the recesses positions the tool so that the edges 86 of the segments strike the nose of the tool and remove the metal from the tool by impact and without "burning" the metal. I have found that this action results in a smooth and sharp cutting edge being formed on the tool. The template 63 is in a position to engage the straight edge 80 to prevent the tool from moving into the recesses an abnormal amount. The successive impacts of the segments of the grinding wheel engaging the tool, very rapidly cuts away or removes the metal until all operative portions of the template 63 engage the straight edge 80. If a greater amount of metal is to be removed from the tool than may be accomplished at one operation, the operator transfers the tool holder 60 to the support 70 and readjusts the tool 71 into engagement with the abutment plate 71. After such re-adjustment is made, the tool holder 60 is again placed upon the support 78 adjacent the grinding wheel 18 and a further grinding operation effected to remove the desired amount of metal predetermined by the setting of the micrometer gage 74.

I have found that during a grinding operation, the tool holder 60 is vibrated to some extent by the successive impacts of the grinding wheel segments engaging the tool as the successive impacts tend to move the tool away from the grind-

ing wheel, but the force exerted by the operator maintains the tool in a position to be continuously engaged by the wheel segments. As soon as the required amount of metal has been removed, the template 63 engages the straight edge and the vibrations of the tool holder cease by reason of the completion of a grinding cycle.

I attribute the successful operation of this method of grinding or configurating tools to the fact that the tool is permitted to move slightly into each successive recess and that the impact of a grinding segment with the tool effects a more rapid and efficient removal of the metal than does the engagement of a tool with an uninterrupted grinding wheel surface.

Another form of apparatus for carrying out the method of my invention for removing hard metal from objects is illustrated in Figures 6 through 9 inclusive. As shown in Figure 6 the apparatus or grinding machine is inclusive of a base 90 having an enlarged receptacle portion 91 to receive the coolant or fluid directed against the grinding wheel 92 through a tube 95 connected to a fluid pump (not shown). The grinding wheel 92 is of the so-called "cup" type and is inclusive of a metal backing plate 93 which is mounted upon a suitable arbor 94 and rotated by driving means (not shown). The frame portion 96 of the machine is provided with two openings 97 and 98 providing two zones of access to the grinding wheel 92. The apparatus is provided with two arcuately-shaped members 99 carried by the frame 96 of the machine and each is provided with a semi-spherically shaped tool holder support 100. Each of the members 99 is adjustable about a center lying in a plane passing through the axis of rotation of the grinding wheel 92 and each may be selectively locked in an adjusted position by locking mechanism (not shown) manipulated by handle 101. Each member 99 is provided with a straight-edge or abutment plate 104 adapted to be engaged by a template carried by a tool holder of the same character as shown at 60 in Figure 1. The adjustment of members 99 is for the purpose of obtaining various angles of relief for tool bits.

The grinding wheel as utilized in this form of apparatus is preferably fabricated of several individual abrasive or grinding units or segments 106 of the configuration shown in Figure 9. In the embodiment shown in Figures 7 and 8, eight abrasive units or segments 106 are employed which are spaced apart or separated by spacing members 107 to secure the units in spaced relation. The spacing blocks 107 are held in place by means of screws 108 threaded into openings provided in the backing plate 93. Each of the abrasive units 106 is provided with an inwardly extending projection 110 having an angularly disposed arcuate surface 111. Means are provided for securing the units 106 in position on the backing plate, said means being in the form of an annular securing ring 112 which is formed with a peripheral surface 114 angularly arranged to fit the arcuate surfaces 111 of the units or segments, as particularly shown in Figure 8. The annular member 112 is securely held to the backing plate 93 and in engagement with the units 106 by means of screws 115 threaded into suitable openings formed in the plate 93. As illustrated in Figures 6 through 9 inclusive I have found it preferable to use independent segments 106 suitably spaced for utilization with the grinding apparatus shown in Figure 6 for grinding hardened tool bits of the

character shown at 116 in Figure 8. It is to be understood that the tool bit 116 is carried by a tool and template supporting unit of the character shown at 60 in Figure 1. A cup type wheel of a character adaptable for use with the apparatus shown in Figure 6 may be used in which portions of the abrasive unit may be spaced through the provision of radial recesses formed in the grinding wheel in the same manner as in the wheel 18 shown in Figure 4. However I have found it practical to utilize the form shown in Figures 7 through 9 inclusive for a cup-type wheel, for the reason that the independent units 106 may be quickly and easily replaced when the same have been worn down.

The principle of operation and method of grinding hardened tools on the apparatus illustrated in Figures 6 through 8 inclusive is the same as that employed in utilizing the apparatus illustrated in Figures 1 through 5 inclusive, i. e. an abrading or removal of metal from the tool bit by impact of the edges 117 of the units 106 when the abrasive unit is rotating in one direction, and the impact of edges 118 of units 106 when the abrasive unit is rotating in the opposite direction. It is to be understood that the driving means for rotating the grinding unit in the apparatus shown in Figure 6 is of a reversible character, so that the zones 97 and 98 provide for use of diametrically opposed grinding positions on the cup wheel through the employment of a template and tool holder mounted upon either of the ball-shaped supports 100.

It is apparent that, within the scope of the invention, modifications and different arrangements may be made other than is herein disclosed, the present disclosure is illustrative merely, the invention comprehending all variations thereof.

What I claim is:

The method of grinding a hardened form tool of the character described which includes advancing said tool by yielding pressure against a rotating grinding wheel having grinding zones spaced apart circumferentially a distance greater than the dimension of the tool in the direction of rotation of the wheel to cause the tool to engage said grinding zones and to enter the spaces between them in response to said pressure so that the leading edges of said zones by successive impacts with said tool will vibrate the latter to remove metal from said tool by such impacts and by abrasion without objectionable burning of the tool or glazing of the wheel, and regulating the amount of metal removed from said tool by positively limiting the degree to which said tool is advanced in the direction of said wheel by said pressure.

CLIFFORD L. GARRISON.
